UNITED STATES PATENT OFFICE.

LUDWIG S. SCHMITTHENNER, OF DARMSTADT, GERMANY.

CHESSMAN.

SPECIFICATION forming part of Letters Patent No. 361,721, dated April 26, 1887.

Application filed December 9, 1886. Serial No. 221,118. (No model.)

To all whom it may concern:

Be it known that I, LUDWIG S. SCHMITTHENNER, a citizen of the German Empire, residing at Darmstadt, Germany, have invented 5 new and useful Improvements in Chessmen, of which the following is a specification.

This invention relates to improvements in chessmen; and it consists in the features set forth in the following specification and claim 10 and illustrated in the accompanying drawings, in which—

Figures 1, 4, 7, 10, and 13 are side elevations of chessmen containing my invention. Figs. 2, 5, 8, 11, and 14 are respectively vertical central sections of Figs. 1, 4, 7, 10, and 13. Fig. 3 is an inverted plan view of a chessman. Figs. 6, 9, 12, and 18 are inverted plan views of chessmen, the material covering the weight being removed. Fig. 15 is an inverted 20 plan view of a chessman, the material covering the weight being partly displaced, exposing part of the weight. Figs. 16 and 17 are respectively a side elevation and a vertical central section of a modification.

Similar letters indicate corresponding parts.

The letter *a* indicates the body of the chessmen, having any suitable well-known or ornamental configuration, and representing the usual figures, such as pawn, rook, knight, 25 bishop, king, or queen.

Each chessman is provided with a foot, *d*, having a weight, *c*. The weight *c* rests in a suitable cavity or hollow in the foot *d*. Said weight consists of any suitable dense material—such, for example, as lead or iron. Said weight can be poured into the cavity in the foot *d* in a molten condition and allowed to harden in the foot, whereby the weight will grip or bite into the foot and be retained 35 therein. Said weight may, however, be fastened to the foot in other ways—as, for example, by screwing, by pins, dowels, or other suitable means.

To conceal the weight from view and to prevent the weight from scraping or injuring such bodies—for instance, as a chess-board—some soft material forming a covering, *b*, is applied over the weight. Said covering *b* may consist of such material, for example, as cloth, leather, parchment, paper, and the like, and be suitably attached—as, for example, by means of adhesive material—so as to cover the weight *c*.

By making the weight *c* sufficiently heavy

the chessmen, if by accident or otherwise they 55 are knocked over, will be righted by the weight *c*, so as to occupy an upright position. Said chessmen are thus not liable to be knocked over by any jar, such as the moving of the chess-board or table on which they are placed. 60 If any such chessman should be knocked onto the floor, the weight will cause each such chessman to rest upright on the floor at the place of falling, so that said chessman will not roll away and become lost.

The chessmen may be made of any suitable material, such as hard rubber, wood, paper-pulp, or other well-known suitable substances.

In the modification shown in Fig. 17 the chessman is hollow or its body is hollow, whereby the weight of the chessman is reduced, and the weight *c* can more readily right the chessman. A plug or cork, *e*, suitably inserted into the chessman prevents any part of the weight *c* from passing toward the upper 75 part of the chessman.

To enable the weight *c* to readily right the chessmen, the foot *d* of each chessman is made of ovoid or egg-shaped resemblance, but with a flat bottom, as seen in the drawings.

The opening for insertion of the weight *c* is made in the flat under side of the foot *d*, and to this flat bottom is attached the soft covering *b*, that conceals the weight and prevents it from scratching the chess-board.

I am aware that cupidors, toy eggs, and what are known as "Chinese mandarins" have been weighted to render them self-righting, and I am also aware that chessmen have been weighted and cloth-covered at their bases to 90 give them more stability; but such are not self-righting. These constructions therefore I disclaim.

What I claim as new, and desire to secure by Letters Patent, is—

A self-righting chessman provided with an ovoid weighted foot having a flat bottom and a soft covering attached to the bottom, to conceal the weight and prevent it from scratching the chess-board, substantially as shown and 100 described.

In testimony whereof I have hereunto set my hand and seal in the presence of two subscribing witnesses.

LUDWIG S. SCHMITTHENNER. [L. S.]
